UNITED STATES PATENT OFFICE

2,605,368

EMERGENCY ADAPTER FOR DISTRIBUTORS

Emerson R. Scott, Chicago, Ill., assignor of one-half to Earl Haney, Chicago, Ill.

Application January 8, 1951, Serial No. 204,999

3 Claims. (Cl. 200—21)

1

The present invention relates to new and useful improvements in distributors for engines of motor vehicles and more particularly to an emergency adaptor for placing on the distributor and provided with an auxiliary set of distributor points and condenser adapted for connecting to the ignition system of the engine in place of the regular points and condenser as an emergency repair therefor.

An important object of the invention is to provide an emergency adaptor of this character which may be easily and quickly installed on the distributor without the aid of a skilled mechanic and without changes or alterations in the construction of the distributor.

A further object is to provide an emergency adaptor which is placed between the distributor cap and base and in which the auxiliary distributor points and condenser function in place of the regular points and condenser.

Another object is to provide a device of this character of simple and practical construction, which is efficient and dependable in operation, relatively inexpensive to manufacture and otherwise well adapted for the purposes for which the same is intended.

These, together with various ancillary objects and features of the invention which will later become apparent as the following description proceeds, are attained by the device, a preferred embodiment of which has been illustrated by way of example only in the accompanying drawings, wherein:

Figure 1 is a side elevational view showing the emergency adapter in its relative position for assembly between the base and cap of a distributor;

Figure 2 is an enlarged vertical sectional view showing the adaptor in assembled position;

Figure 3 is a group perspective view of the shaft and connector for the adaptor; and

Figure 4 is a top plan view of the adaptor.

Referring now to the drawing in detail, wherein for the purpose of illustration I have disclosed a preferred embodiment of my invention, the numeral 5 designates the base of a conventional type of distributor which is provided with the usual vertical shaft 6 having a hexagonal cam 7 for making and breaking the distributor points 8. A terminal 9 is provided on the outside of the base for connecting to the ignition system of an engine (not shown) and the distributor also includes a condenser 10 carried by the base. The upper end of shaft 6 above cam 7 is formed with a flat side 11 to provide a drive connector for the usual rotor of the distributor.

2

A cap 12 is usually secured on base 5 by resilient catches 13 snapped over a flange 14 on the cap and when a failure of the regular points 8 or condenser 10 occurs, an emergency adaptor, 5 shown generally at 15, is placed between base 5 and cap 12 and comprises a hollow auxiliary base 16 having external lugs 17 engaged by the catches 13 of the regular base and the auxiliary base is provided with similar resilient catches 18 10 engaging the flange 14 of the cap to thus hold the cap 12 and auxiliary base 16 in assembled relation on the regular base 5.

Auxiliary base 16 is provided with a plate or platform 19 which is cast or otherwise secured 15 in the base and a bushing 20 is supported centrally in the plate and in which a hollow shaft 21 is journaled.

A collar 22 is secured to the lower end of shaft 21 in a position to extend downwardly therefrom by means of a transverse pin 23 and the collar and shaft are connected to each other for rotation as a unit by a flattened side 24 on the shaft confronting an internal flattened face 25 in the collar. The lower end of collar 22 is 25 sleeved over the upper end of shaft 6 with their flattened faces confronting to drive shaft 21.

A hexagonal cam 26 is also secured to the upper end of shaft 21 and the shaft projects above the cam and is also flattened as at 27 to rotatably connect the rotor 28 thereto, as shown in 30 Figure 2.

An auxiliary set of distributor points 29 and condenser 30 are also mounted on plate 19 and a terminal 31 projects from one side of the auxiliary base 16 for connecting to the ignition system of the engine.

Accordingly should the regular points 8 or condenser 10 of the distributor fail, the rotor is removed from the upper end of shaft 6 and the 40 emergency or auxiliary base 15 placed in position between the regular base and cap 12. The rotor is placed on the upper end of shaft 21 of the emergency base and the ignition system is disconnected from terminal 9 of the regular base 5 and connected to the terminal 31 of the emergency base and the distributor will then function in the usual manner.

In view of the foregoing description taken in conjunction with the accompanying drawings it 50 is believed that a clear understanding of the device will be quite apparent to those skilled in this art. A more detailed description is accordingly deemed unnecessary.

It is to be understood, however, that even 55 though there is herein shown and described a

preferred embodiment of the invention the same is susceptible to certain changes fully comprehended by the spirit of the invention as herein described and the scope of the appended claims.

Having described the invention, what is claimed as new is:

1. An emergency adaptor for engine distributors of a type having a main base equipped with circuit making and breaking means and a cap for the base, and said adapter comprising an auxiliary base adapted for assembly between the main base and the cap and equipped with duplicate circuit making and breaking means, said main and said auxiliary bases each including an actuating shaft for the respective circuit making and breaking means, and means coupling said shafts to each other.

2. An emergency adaptor for engine distributors of a type having a main base equipped with circuit making and breaking means and a cap for the base, and said adapter comprising an auxiliary base adapted for assembly between the main base and the cap and equipped with duplicate circuit making and breaking means, each of said circuit making and breaking means including a shaft adapted for interchangeably

mounting a rotor on its upper end, and a shaft coupler connecting said shafts to each other.

3. An emergency adaptor for engine distributors comprising a hollow body having a platform therein, said body being adapted for assembly between the regular base and cap of a distributor, a shaft journaled centrally in the platform, a cam on the upper portion of the shaft, a set of distributor points and a condenser mounted on the platform in a position for opening and closing the points by the cam, a terminal for the points and condenser adapted for connecting to the ignition system of the engine, said shaft having a flat side at its upper end adapted for attaching a rotor thereto, and a collar at the lower end of the shaft adapted for coupling to the shaft of the regular base.
